UNITED STATES PATENT OFFICE.

EDWARD CALDERIO, OF GARFIELD, NEW JERSEY, ASSIGNOR OF ONE-HALF TO EDWARD H. WHITTIER, OF PASSAIC, NEW JERSEY.

AUTOMATIC BLOWER ATTACHMENT FOR PUNCH-PRESSES.

1,279,981.

Specification of Letters Patent. Patented Sept. 24, 1918.

Application filed May 8, 1918. Serial No. 233,402.

To all whom it may concern:

Be it known that I, EDWARD CALDERIO, a citizen of the United States, and a resident of Garfield, in the county of Bergen and 5 State of New Jersey, have invented a new and Improved Automatic Blower Attachment for Punch-Presses, of which the following is a full, clear, and exact description:

This invention relates to attachments for 10 reciprocating punch or die presses, and has particular reference to means for keeping the dies from becoming excessively hot and also blowing away and cleaning the dies of any dirt or foreign matter, which may have 15 been deposited thereon.

Among the objects of the invention is to provide an attachment for a punch press including a device or means to automatically project a stream or streams of cooling fluid 20 such as air upon or against the active co-operating elements of the machine at a time when these elements are separated.

Another object of the invention is to provide a nozzle with automatic means to move 25 it into position between the active elements of the press when they are separated and back out of the path of the moving elements of the press when the press is making its down stroke.

30 With the foregoing and other objects in view the invention consists in the arrangement and combination of parts hereinafter described and claimed, and while the invention is not restricted to the exact details of 35 construction disclosed or suggested herein, still for the purpose of illustrating a practical embodiment thereof reference is had to the accompanying drawings, in which like reference characters designate the same parts 40 in the several views, and in which—

Figure 1 is a side elevation of my improvement attached to a reciprocating punch press shown in outline, full lines indicating the position of the attachment when the 45 press plunger is up and indicating in dotted lines the position that is caused to be assumed by the downward movement of the press plunger; and

Figs. 2 and 3 are vertical transverse sectional views on the corresponding lines of Fig. 1.

Referring now more particularly to the drawings, I show at 10 the base or fixed portion of the press having one die member 55 11, and at 12 I show the upper reciprocating

member or plunger of the press carrying the other coöperating die member 13. As to the particular construction or utility of the press I am not specially concerned except to observe that the member 12 is caused by some suitable power means to 60 reciprocate toward and from the base 10 to bring the die members 11 and 13 into the desired coöperative relationship and thereby at each upward movement of the plunger a 65 free space is observed between the tool members 11 and 13 into which the work or material to be operated upon is introduced or adjusted.

14 indicates a flexible tube or hose leading 70 from any suitable source of cool fluid supply, and into the end of the tube 14 is fitted a pipe 15 of any suitable length or caliber. The free end of the pipe 15 is fitted with a nozzle 16 having groups of jet holes 16' 75 formed mainly in its upper and lower surfaces, whereby the cool fluid such as air conveyed through the tube, pipe, and nozzle 16 will be delivered against the spaced faces of the tool members 11 and 13 when the nozzle 80 occupies a position in the space between the same as shown in full lines.

Any suitable means may be provided to carry the nozzle automatically into and out of said space coincidentally with the usual 85 reciprocations of the member 12. To this end I provide upper and lower anchor blocks 17 and 18 fixed respectively in any suitable manner to the plunger 12 and base 10, each of the anchor blocks being provided 90 with a vertical series of holes 17' or 18'.

19 indicates a cross head fixed to the pipe 15 as by means of a set screw 20. The cross head is provided with laterally projecting 95 trunnions 21 upon which are journaled the inner ends of a main pair of toggle links 22 and 23 whose upper and lower ends are pivoted respectively at 24 and 25 to the aforesaid anchor blocks. The selection of 100 the holes 17' and 18' for the pivots 24 and 25 is determined according to the extent of reciprocation of the plunger 12, the point of adjustment of the cross head 19 on the pipe 15, and other conditions that any mechanic 105 will meet in practice. The inner ends of the toggle links 22 and 23 are retained on the trunnions by any suitable means such as washers 26 and nuts 27.

The pipe 15 is maintained preferably in a 110

substantially horizontal position in order to best control its movements and operation. To this end I provide a pair of auxiliary toggle links 28 and 29 whose inner or adjacent ends are pivoted at 30 to the trunnions of a cross head 31 having a hole 32 through which the pipe 15 is adapted to pass with relative freedom as a guide. The upper and lower ends of the auxiliary toggle links are pivoted at 33 and 34 to the intermediate parts of the main links 22 and 23. The auxiliary links are held upon the trunnions 30 by means of washers 35 and nuts 36. The links of each pair are preferably of equal length and therefore with the pipe 15 secured to the cross head 19 the pipe will be carried in a position always parallel with itself and as before stated preferably horizontal.

The nozzle will thus be brought into and out of position directly between the two elements 11 and 13, the arrangement of the toggle links being such that when the plunger is up the nozzle will be in position directly in the space so as to direct the jets of cooling air against the tool members. This space ordinarily is wide enough to admit the work without obstruction and the moment the plunger begins its downward movement the movement of the anchor block 17 toward the block 18, breaking the toggle links, will carry the nozzle out of the path of the plunger. The operation is simple, sure and reliable and entails no special attention on the part of the machinist or operator of the press.

I claim:

1. The combination with a reciprocating

press including stationary and movable parts and coöperating tool members connected to the respective parts, of a cooling air nozzle, and means connected to the respective movable and stationary parts of the members to automatically bring the nozzle into cooling position directly in the path of the movable part when the relatively movable parts of the press are separated.

2. The combination with the relatively fixed and movable members of a reciprocating press and tools carried thereby, of a cooling fluid nozzle adapted to coöperate with the tools aforesaid, and means to automatically carry said nozzle into and out of the space between the tools coincidentally with the reciprocations of the movable part of the press, said carrying means including toggle members connected to the nozzle, and means pivotally connecting the toggle members to the fixed and movable members of the press.

3. The combination with the relatively fixed and movable members of a press and tool members carried thereby, of a cooling fluid nozzle having upper and lower jet holes directed toward the several tool members, a pipe to which the nozzle is secured, a cross head fixed to the pipe, a pair of anchor blocks secured to the respective fixed and movable parts of the press, a pair of toggle links pivoted respectively to the cross head and said blocks, and means coöperating with said pipe and toggle links to maintain the pipe in substantial parallelism while it is being moved by the toggle links into and out of the space between the tool members.

EDWARD CALDERIO.
